UNITED STATES PATENT OFFICE

BYRAM S. DICKERSON, OF INDIANAPOLIS, INDIANA

RAIL JOINT

Application filed December 16, 1930. Serial No. 502,794.

This invention relates to rail joints for railway tracks and an object of the invention is to provide a splice plate which will eliminate jolts and noise incident to the cracks or spaces between the ends of rails and to provide the smooth rolling surface which would obtain if the rails were continuous.

A further object is to provide a rail joint having greater strength than joints heretofore made.

A further object is to provide a rail joint in which contraction and expansion due to changes of temperature will be provided for without causing objectionable gaps between the rails.

Further objects and advantages will become apparent as the description proceeds.

Referring to the accompanying drawings, which are made a part hereof and on which similar reference characters indicate similar parts,

Figure 1 is a plan view showing the preferred embodiment of the invention,

Figure 2, a side elevation of the same,

Figure 3, a section on line 3-3 of Figure 2,

Figure 4, a section on line 4-4 of Figure 2,

Figure 5, a section on line 5-5 of Figure 2,

Figure 6, a side elevation showing a modified form of the device,

Figure 7, a section on line 7-7 of Figure 6, and

Figures 8 and 9 are sections of further modified forms of the device.

In the drawings numeral 10 indicates a railway rail and 11 indicates as a whole a splice bar for securing adjacent ends of rails together. The head of each rail is cut away at 12 and the base is cut away at each side adjacent the end at 13. The splice plates

11 are provided with top portions 15 which engage in the cut away portion 12 of the rail.

The ends of the portions 15 of the plates are cut at 16 to conform to the cut away portion of the rails at their ends so that the splice plates fit neatly within the cut away portions of the ends of the rails. The rails, however,

may contract and expand since a suitable clearance is allowed for the necessary expansion due to changes in temperature. The splicing plates at their ends seat upon the

base flanges of the rails as shown at 17. The central portion of the splice plates, however, extend down through a cut-away portion 18 of the bases of the rails and the bases 19 of these plates lie in the plane of the base of the 55 rails so that they may rest firmly upon the railroad ties. Holes are provided in the splice plates, as shown at 20, by means of which they are bolted in the usual manner to the rails. From the construction defined it 60 will be apparent that there is no break in the top of the rail since the wheels of the locomotive will ride upon the portion 15 of the splicing plates prior to reaching the space at 22 between the ends of the rails. There will 65 therefore be a continuous solid bed for the wheel with no clicking or jarring effect as the wheels pass over the rail joints.

In the modified form of the invention, as shown in Figure 6, the splicing plates have 70 depending flanges or sides 23 which extend well down between the ties 24 so that with plates of this structure the joints between the rails do not necessarily have to be immediately vertical over a tie since the flanges fully 75 reinforce the splice plates and make them sufficiently strong to support the weight of the train. In all forms there is a shoulder portion 25 which rests against a corresponding ledge at 26 which forms a part of the 80 base of the rail. In this form as also in the preferred form the portion 15 of the splice plate extends in so that a shoulder 27 rests against an outer portion of the top of the rail so that a part of the weight of the train is 85 supported on the rail instead of all being supported by the splicing plates.

In the form of the invention shown in Figure 8 the inwardly extending portion 28 of the splicing plates rests directly upon the top 90 of the rail, a portion being cut-away at 29 so that the entire weight of the train is carried by the splicing plates. The splicing plates rest at their lower ends upon the base of the rails as shown at 30.

In the form shown in Figure 9 the inwardly extending portions 31 of the splicing plates rest upon corresponding ledges 32 of the tops 95 of the rails but a portion of the top of the rail extends up as shown at 33 so that the 100

rail also supports part of the weight of the train. In all forms of the invention, however, the top of the rail provides a continuous track so that all jarring is eliminated.

5 It will be obvious to those skilled in the art that various changes may be made in my device without departing from the spirit of the invention and therefore I do not limit myself to what is shown in the drawings and described in the specification, but only as indicated by the appended claims.

Having thus fully described my said invention, what I claim as new and desire to secure by Letters Patent, is:

15 1. A rail joint comprising the combination with two opposing rail ends, each having a portion of its head and base cut away for a desirable length from the end, providing a sloping shoulder on each side of its head and 20 base, a pair of vertical splice plates having a minimum depth at the middle section equal to the full depth of the rails, a portion of the upper edge of each plate adapted to form a part of the wheel tread in lieu of the cutaway 25 rail heads, the inner face of each plate being fashioned to fit the contour of the rail webs and the cutaway portions of the heads and bases of the rail ends on their respective sides for the total length of the cutaway portions 30 of both rail ends, and extending at each end in a reduced section adapted to fit snugly against the under face of the head, the web, and top surface of the base, where the rail is of full section, and means for holding the splice plates securely against the rail ends allowing only slight longitudinal movement of the rail ends relative to the splice plates, substantially as set forth.

2. A rail joint comprising the combination with two opposing rail ends, each having a portion of its head and base cut away thereby forming a projection on each side of its head and base, a pair of vertical splice plates substantially similar in design, having a minimum depth at the middle section equal to the full depth of the rails, a portion of the upper edge of each plate adapted to form a part of the wheel tread, on its respective side, in lieu of the cut away rail heads, the middle 40 cross section area of each plate of such symmetry, to the vertical and horizontal axes through the center of gravity of the area, that the neutral axis resulting from an applied vertical bending movement is substantially horizontal, and each plate resists such vertical bending according to the principles of true girder action, means for a positive transmission of strain resulting from an applied vertical bending movement from each splice 45 plate to the other through the reduced rail sections, means for holding the splice plates securely against the rail ends allowing only slight longitudinal movement of the rails relative to the splice plates, substantially as set forth.

3. A rail joint comprising the combination with two opposing rail ends, each having its head and base cut away on each side for a desirable length from the end, the planes of the cutaway surfaces of the head if produced forming an angle one with the other, their intersection being a straight line above the rail head, the angle of intersection providing a projection, or shoulder, on the lower part of the remaining portion of the rail head on each side relative to the web, the planes of the cut away surfaces of the base if produced forming an angle one with the other, their intersection being a straight line below the rail base, the angle of intersection providing a projection, or shoulder, on the upper part of the remaining portion of the rail base on each side relative to the web; a pair of vertical splice plates having a minimum depth at the middle section equal to the full depth of the rails, a portion of the upper edge of each splice plate adapted to form a part of the wheel tread in lieu of the cut away rail heads, the inner face of each plate being grooved to conform with the contour of the cutaway rail heads and bases for the horizontal distance required to fit the two opposing cut away portions of the rail ends, and extending at each end in a reduced section to fit snugly against the web of the rail, the under surface of the head and the upper surface of the base where the rail is of full section, means for holding the splice plates securely against the rail ends allowing only slight longitudinal movement of the rails relative to the splice plates, substantially as set forth.

4. A rail joint comprising the combination with two opposing rail ends, each having its head cut away on each side, the planes of the cut away surfaces of the head if produced forming an angle one with the other, their intersection being a straight line above the rail head, the angle of intersection providing a projection, or shoulder, on the lower part of the remaining portion of the rail head on each side relative to the web; a pair of splice plates, a portion of the upper edge of each plate adapted to form a part of the wheel tread on its respective side, in lieu of the cut away rail heads, the inner face of each plate being grooved to fit the contour of the cut away rail heads for the horizontal length of the two opposing cutaway rail heads, and extending at each end in a reduced section to fit snugly the web of the rail, the under surface of the head and upper surface of the base, where the rail is of full section; means for holding the splice plates securely against the rail ends allowing only slight longitudinal movement of the rails relative to the splice plates, substantially as set forth.

5. A rail joint comprising the combination with two opposing rail ends, each having its head cut away on each side for a desir-

- able length from the end, leaving a narrow strip of wheel tread in the middle of the head, a sloping shoulder on each side thereof; a pair of splice plates which may be similar in design, a portion of the upper edge of each plate adapted to form a part of the wheel tread, on its respective side, in lieu of the cut away rail heads, the inner face of each plate grooved to fit the contour of the cut away rail heads for a horizontal length equal to the length of the two opposing cut away rail heads, and extending at each end in a reduced section to fit snugly the web of the rail, the under surface of the head and upper surface of the base, where the rail is of full section, means for holding the splice plates securely against the rail ends allowing only slight longitudinal movement of the rails relative to the splice plates, substantially as set forth.
6. A splice plate for the ends of railway rails having a longitudinal rib adapted to seat on a portion of the base of the rail and having a depending edge adapted to extend through a cut away portion of the base and a longitudinal shoulder adapted to extend over a cut-away portion of the rail, the top of said shoulder lying flush with the top of the rail and serving as a part of the top of the rail to support the train, substantially as set forth.
7. A rail joint comprising the combination with two opposing rail ends, each rail end being reduced in section by having its head cut away on each side thereof, a pair of splice plates designed to form an integral wheel tread in lieu of the cut-away heads and to extend at each end in a reduced section to fit snugly the under surface of the head, the web, and the upper surface of the base where the rail is of full section, the inner face of each plate rabbeted to conform to the projections, or shoulders, which obtain from leaving a portion of the head on each side throughout the reduced rail end sections, means of holding the splice plates securely against the rail ends allowing only a slight longitudinal movement of the rails relative to the splice plates, substantially as set forth.
8. A rail joint comprising the combination with two opposing rail ends, each rail end being reduced in section by cutting away a portion of the head and base on each side thereof; a pair of splice plates which may be similar in design, each having a minimum continuous depth throughout the middle section equal to the full depth of the rails, and extending at each end in a reduced section to fit snugly the under surface of the head, the web, and the upper surface of the base where the rail is of full section, a portion of the upper edge of each plate adapted to form a part of the wheel tread on its respective side in lieu of the cut away rail heads, the inner face of each plate rabbeted to conform to the projections, or shoulders which obtain from leaving a portion of the head and base on each side of each rail throughout the reduced rail end sections, and means for holding the splice plates securely against the rail ends allowing only a slight longitudinal movement of the rails relative to the splice plates, substantially as set forth.
9. The combination of rail ends having a portion of the tops of the rails cut off, of plates having longitudinal ribs adapted to fit over the cutaway portions of the top of the rail, said ribs serving with the remaining portion of the rail for supporting the weight of trains passing over the rails and to provide a smooth joint, substantially as set forth.
- In witness whereof, I have hereunto set my hand at Indianapolis, Indiana, this 13th day of December, A. D. nineteen hundred and thirty.
- BYRAM S. DICKERSON.
